UNITED STATES PATENT OFFICE.

LEE S. CHADWICK, OF EAST CLEVELAND, OHIO, ASSIGNOR TO THE CLEVELAND METAL PRODUCTS COMPANY, OF CLEVELAND, OHIO, A CORPORATION OF OHIO.

OIL-BURNER.

1,291,403.

Specification of Letters Patent. Patented Jan. 1, 1919.

Application filed March 6, 1915. Serial No. 12,650.

To all whom it may concern:

Be it known that I, LEE S. CHADWICK, a citizen of the United States, residing at East Cleveland, in the county of Cuyahoga and State of Ohio, have invented a certain new and useful Improvement in Oil-Burners, of which the following is a full, clear, and exact description, reference being had to the accompanying drawings.

10 This invention relates to oil stoves and more particularly to stoves of the type wherein perforated commingling tubes are employed for the purpose of producing a blue flame, in a manner well known in the art. It is the general purpose of this invention to provide a burner of this character wherein the top of the wick and the surrounding wick tubes will be kept cool and wherein this result may be secured even 15 should either or both of the commingling tubes become unseated to such an extent as to admit air beneath the bottom or bottoms thereof. This necessarily results in maintaining the combustion more uniform and efficient 20 and in prolonging the life of the wick. A further and more specific object of the invention is to provide an improved seating arrangement for the commingling tubes; also an improved construction of wick tubes. 25 Further and more generally stated, the invention may be defined as consisting of the combinations of elements set forth in the claims appended hereto and illustrated in the drawings forming part hereof, wherein Figure 1 represents a vertical sectional view 30 taken through a burner constructed in accordance with my invention; Fig. 2 a cross sectional view corresponding to the line 2-2 of Fig. 1, the parts at the right hand 35 side of the burner being broken away; and Fig. 3 a sectional detail of a modified construction of the upper ends of the wick tubes and of the parts coöperating therewith.

Referring to the drawings forming part 40 of this specification, 1 denotes an inner and 2 an outer wick tube forming therebetween an annular space to which oil may be supplied through the pipe 3 and a lateral supply connection 4 secured to the outer wick tube and 45 provided with a bore communicating with an opening 5 in said wick tube. The burner is secured to the pipe 3 by means of the hook 6 which is secured to and depends from the inner tube and by means of the con-

nection 4, the manner of securing the burner 50 to the tube being substantially the same as that disclosed in Jeavons Patent No. 951,612 issued March 8th, 1910. The width of the space between the tubes 1 and 2—with the exception of the upper portions of said tubes—is considerably greater than the thickness of the wick 7 which is interposed between said tubes, thus providing a well for the reception of oil and a space within which the wick and its carrier 8 may freely 55 rise and fall. At a suitable distance below their tops, the wick tubes are bent—the inner tube downwardly and inwardly as shown at 9 and the outer tube downwardly and outwardly as shown at 10, the metal of the tubes 60 being doubled or bent upon itself thereby to form downwardly inclined inner and outer seats for commingling tubes, to be described hereinafter. Above these seats, the inner tube is bent outwardly, as shown at 11, and 65 the outer tube inwardly, as shown at 12, whereby the upper portions of such tubes are in substantial engagement with and form 70 a contacting guide for the upper end of the wick, as indicated at 13 and 14. The extreme upper end of the inner wick tube is curled inwardly, thereby providing a rounded inwardly projecting bead 15 at its upper 75 end and the extreme upper end of the outer wick tube is curled outwardly, thereby providing 80 a rounded outwardly projecting bead 16.

17 denotes a perforated inner commingling tube which is provided near its bottom and above the top of the wick tubes with a 85 perforated diaphragm 18 and at its top with a cap 19 which may have a central perforation 20. The cap 19 may be conveniently fitted within the top of the inner commingling tube by means of a downwardly projecting flange 21 which fits snugly within the top of said commingling tube and is shown 90 as seated within the lugs 22, which may be struck from the metal constituting said commingling tube.

100 23 denotes the outer commingling tube, this tube, when seated, preferably extending above the inner commingling tube. A drum 24 having a large opening 25 in the top thereof surrounds the commingling tubes and is 105 provided with an annular bottom 26 which projects inwardly toward the outer wick tube, thence downwardly as shown at 27 be-

- low the seat 10, and thence inwardly below said seat, as indicated at 28, forming an annular air receiving space 29 with the outer wick tube below said seat. The bottom plate 5 26 is provided with perforations 26^a for admitting air to the space surrounding the outer commingling tube. Within the inner wick tube there is located an air distributor 30, said distributor being of the shape of an 10 inverted bowl having a central opening 31 in the top thereof and having its inverted wall or skirt extending substantially parallel with the inner wick tube to which it may be secured by means of the channel members 15 32, said members being preferably arranged with their flanges bearing respectively against the inner wick tube and the wall of the distributor and being secured thereto in any convenient manner, as by soldering or 20 brazing. The upper end of this distributor is substantially flush with the bottom of the inner commingling tube when the latter is resting upon its seat.
- The commingling tubes and the drum are 25 shown as connected by means of cross rods 33, 34 whereby they may be handled as a unitary structure without disturbing their proper relation to one another and to the wick tube seats.
- 30 With the parts arranged as described, it is believed that the general operation will be apparent. Air which is necessary to produce the combustion of the gases or vapors between the tubes 17 and 23 is supplied to the 35 outer tube through the annular opening or slot 29 and beneath the seat 10. Impinging upon said seat it is directed downwardly and outwardly and thence upwardly to the outer surface of the commingling tube 23, 40 the perforations whereof it enters and operates in the usual manner toward the production of a blue flame. Additional air for the outer tube 23 is admitted through the openings 26^a.
- 45 The air which ascends within the inner wick tube flows in greater part in a substantially annular sheet between the distributor 30 and the inner wall of said inner wick tube, impinging upon and beneath the seat 50 9 and being deflected downwardly and inwardly thereby and thence passing upwardly into the interior of the inner commingling tube. Some air—a limited quantity—passes through the opening 31, and the major portion 55 of the air within the inner commingling tube passes into the space between said tube and the outer tube and operates in the usual manner toward the production of a blue flame.
- 60 It will be seen that the top portions of the inner and outer wick tubes and the seats for the commingling tubes particularly are subjected to upwardly moving currents of air tending to keep these parts cool.
- Attention has been invited hereinbefore to

the inwardly and outwardly projecting beads 15 and 16. These beads nearly contact with their respective commingling tubes, forming an extremely narrow space or slit therewith. Should any matter accumulate on either or both seats 9 and 10 whereby the commingling tubes will be tilted or unseated, the air entering through this space might encounter vapors in such quantity as to cause combustion thereof below the tops of the tubes. By the construction shown and described herein, however, the spaces which are provided between the tops of the wick tubes and their corresponding commingling tubes are so narrow as to cause the air which may thus be unwittingly introduced to be discharged in a narrow rapidly moving sheet which prevents the maintenance of a flame below the tops of the burner tubes.

The narrowness of the slits provided between the tops of the inner and outer wick tubes and their respective commingling tubes prevents anything but the finest particles of charred wick or other material from passing therethrough. Furthermore, should any material be discharged upon the seats, especially at the time when the commingling tubes are removed, as for purposes of cleaning the wick, the downward inclination of the seats will prevent practically all such material from adhering to or remaining on the seats.

In Fig. 3 I have shown a modification of the invention which differs from that shown in the first two figures of the drawings mainly in the fact that the upper ends of the wick tubes are not made from the same sheet of metal as the lower portions and the seats which are formed at the junction of the upper and lower portions of these tubes are not downwardly inclined. The upper portion 33 of the inner wick tube is formed from a sheet of metal having a bead 34 at its top substantially identical with the bead 15 and having an outwardly projecting flange 35 at its lower end about which the upper end of the tube 1 is crimped, as shown at 36, thereby forming a seat for the commingling tube 17. In like manner the upper end 37 of the outer wick tube 2 is formed from a comparatively narrow sheet of metal having an outwardly projecting bead 38 at its upper end similar to the bead 16 and having at its bottom an outwardly projecting flange 39 about which the upper end of the tube 2 is crimped, as shown at 40. On the seat formed by uniting the top of the tube 2 and the bottom of the tube section 37, the outer commingling tube 23 is supported.

The construction described herein is simple and economical of production but is particularly efficient for the purposes of realizing the objects of the invention. Burners of the type shown herein, while applicable for other purposes, have been found 130

to be advantageous for heating places such as garages and tents, as well as for general heating purposes.

Having thus described my invention, what I claim is:—

- 5 1. In a burner of the character described, the combination of outer and inner wick tubes, outer and inner commingling tubes seated respectively about and within the 10 outer and inner wick tubes, a drum surrounding and spaced from the outer commingling tube, means in operative relation to the outer wick tube for directing air supplied to the drum along the upper portion 15 of said wick tube and against the seat for the outer commingling tube, and means within the inner wick tube for directing substantially all of the air supplied to the inner commingling tube along and in proximity 20 to the upper portion of the said inner wick tube and along the seat for the inner commingling tube.
2. In a burner of the character described, the combination of outer and inner wick 25 tubes, commingling tubes seated about and within said tubes, respectively, a drum surrounding the outer commingling tube and extending inwardly below the seat for the outer commingling tube and in proximity to 30 the outer wick tube, and an air distributer within the inner wick tube and arranged to direct air along the inner wick tube below the commingling tube seat.
3. In a burner of the character described, 35 the combination of outer and inner wick tubes, outer and inner commingling tubes seated respectively about and within the outer and inner wick tubes, a drum surrounding and spaced from the outer commingling tube, means in operative relation to the outer wick tube for directing air supplied to the drum along the upper portion of said wick tube and against the seat for the outer commingling tube, and means within 40 the inner wick tube forming an annular passageway, within said tube and within and along the seat for the outer commingling tube, for substantially all of the air supplied to the inner commingling tube, where- 45 by an efficient cooling of the upper end of the inner wick tube and of the seat for the inner commingling tube is secured.
4. In a burner of the character described, the combination of outer and inner wick 50 tubes, each having a downwardly inclined seat below the top thereof, and an inner and an outer commingling tube each being of a diameter whereby it will be supported on the corresponding inclined seat of its respective wick tube.
5. In a burner of the character described, the combination of an outer and an inner wick tube each having a seat below the top thereof, the outer wick tube having its upper 55 end projected outwardly and the inner wick tube having its upper end projected inwardly, and an outer and an inner commingling tube adapted to rest respectively upon the seat on the outer wick tube and the seat on the inner wick tube and each 60 forming with the upper end of its respective wick tube a narrow passageway.
6. In a burner of the character described, the combination of an outer and an inner wick tube, and an outer and an inner commingling tube seated about and within said 65 tubes respectively and each forming with the upper end of its respective wick tube a narrow passageway of less width than the space formed between the portion of each commingling tube and the portion of the wick tube below such upper end.
7. In a burner of the character described, the combination of an outer wick tube having below the top thereof a downwardly and 70 outwardly projected seat and having its upper end projected outwardly to form a bead, an inner wick tube having below its top a seat and having its upper end projected inwardly to form a bead, a wick between said tubes, and inner and outer commingling tubes adapted to rest on said seats, respectively, and each forming a narrow passageway with the bead thereabove.
8. In a burner of the character described, 75 the combination of outer and inner wick tubes each having below the top thereof a seat, and outer and inner commingling tubes adapted to rest on said seats respectively and forming with the tops of their respective wick tubes a narrow passageway of less width than the space formed between the lower portion of each commingling tube and the portion of the wick tube above such seat and below such top.
9. In a burner of the character described, 80 the combination of an outer and inner wick tube each having a laterally projecting seat below the top thereof, an outer and an inner commingling tube adapted to rest respectively on said seats, a drum surrounding the outer commingling tube and extending below the seat on the outer wick tube and forming with said wick tube a passageway for air, and a deflector or distributer within 85 the inner wick tube and previously below the seat thereof a substantially vertical passageway for air adjacent to said wick tube.
10. In a burner of the character described, the combination of outer and inner wick 90 tubes each having below the top thereof a laterally projecting seat and converging above said seat to substantially contact with and form a guide for the wick, and outer and inner commingling tubes adapted to rest 95 on said seats.
11. In a burner of the character described, the combination of outer and inner wick tubes spaced apart at their lower portions to provide a free space for the wick and 100
- 105
- 110
- 115
- 120
- 125
- 130

- each having below the top thereof a laterally projecting seat and converging above said seats to substantially contact with and form a guide for the wick, and commingling tubes adapted to rest on said seats and forming with the tops of their respective wick tubes a narrow passageway.
12. In a burner of the character described, the combination of outer and inner wick tubes spaced apart at their lower portions to provide a free space for the wick and each having below the top thereof a laterally projecting seat and converging above said seats to substantially contact with and form a guide for the wick, and commingling tubes adapted to rest on said seats.
13. In a burner of the character described, the combination of outer and inner wick tubes spaced apart at their lower portions to provide a free space for the wick and each having below the top thereof a downwardly and laterally projecting seat and converging above said seat to substantially contact with and form a guide for the wick, and commingling tubes adapted to rest on said seats and forming with the tops of their respective wick tubes a narrow passageway.
14. In a burner of the character described, the combination of outer and inner wick tubes spaced apart at their lower portions to provide a free space for the wick and each having below the top thereof a downwardly and laterally projecting seat and converging above said seats to substantially contact with and form a guide for the wick, and commingling tubes adapted to rest on said seats.
15. In a burner of the character described, the combination of outer and inner wick tubes, outer and inner commingling tubes seated about and within said tubes, respectively, an air distributor within the inner
- wick tube comprising a skirt extending substantially parallel with the upper portion of the tube to form an annular passageway therewith, and means associated with the outer wick tube to provide an annular passageway therewith below the top of said tube.
16. In a burner of the character described, the combination of outer and inner wick tubes, outer and inner commingling tubes seated about and within said tubes respectively, and an air distributor within the inner wick tube comprising a skirt extending substantially parallel with the upper portion of the tube to form an annular passageway therewith, and serving to direct air beneath the seat for the inner commingling tube.
17. In a burner of the character described, the combination of outer and inner wick tubes, outer and inner commingling tubes seated about and within said outer and inner wick tubes, respectively, and below the tops thereof, an air distributor within the inner wick tube and forming therewith an extended annular passageway for air below and adjacent to the seat for the inner commingling tube, and a drum surrounding the outer commingling tube and extending below the seat therefor and providing with the outer wick tube a restricted annular passageway below said seat, the said air distributor extending across the central portion of the inner wick tube and being provided with an aperture whereby a limited quantity only of the air supplied to the inner commingling tube may pass through said distributor.
- In testimony whereof, I hereunto affix my signature in the presence of two witnesses.

LEE S. CHADWICK.
